UNITED STATES PATENT OFFICE.

ALFRED W. HOYER, OF MINNEAPOLIS, MINNESOTA, ASSIGNOR OF ONE-HALF TO PETER J. HOYER, OF CENTERVILLE, SOUTH DAKOTA.

STOVEPIPE-LOCKING DEVICE.

No. 913,822.

Specification of Letters Patent.

Patented March 2, 1909.

Application filed August 10, 1908. Serial No. 447,660.

To all whom it may concern:

Be it known that I, ALFRED W. HOYER, a citizen of the United States, residing at Minneapolis, in the county of Hennepin and State of Minnesota, have invented certain new and useful Improvements in Stovepipe-Locking Devices; and I do hereby declare the following to be a full, clear, and exact description of the invention, such as will enable others skilled in the art to which it appertains to make and use the same.

My invention relates to stove pipe locking devices, and is in the nature of an improvement on the devices set forth and claimed in my prior United States Patent 891,480, issued of date June 23, 1908.

The invention consists of the novel devices and combinations of devices hereinafter described and defined in the claims.

20 In the accompanying drawings which illustrate the invention, like characters indicate like parts throughout the several views.

Referring to the drawings: Figure 1 is a view chiefly in side elevation, but with some parts sectional and with some parts broken away, illustrating my improved stove pipe locking device applied in working position. Fig. 2 is a horizontal section taken on the line x^2-x^2 of Fig. 1. Fig. 3 is a detail view showing the position of one of the anchoring wires and the split end of the bolt to which it is connected. Fig. 4 is a section taken on a line x^4-x^4 of Fig. 3.

The numeral 1 indicates a portion of a stove, such as a sheet iron heater, and the numeral 2 indicates a chimney having the usual pipe flue, preferably lined by a cylindrical sheet metal pipe thimble 3.

The numeral 4 indicates the vertical portion, the numeral 5 indicates the horizontal portion and the numeral 6 the elbow portion of a stove pipe that leads from the flanged smoke outlet passage 1^a of the stove 1 into the chimney flue 3. The elbow portion 6 is shown as a jointed elbow and it will of course, be understood, that the vertical and horizontal portions 4 and 5 respectively, each may be made up of any desired number of pipe sections or joints of standard or of any suitable construction. Rotatively mounted in, and extended diametrically through the lower part of the vertical portion 4 of the stove pipe, is a windlass shaft 7, which is preferably of the construction disclosed in

my said prior patent, and which is adapted 55 to be held against rotation by means of a lock dog 8, that engages a small ratchet wheel 9 on one end of said windlass shaft. The numeral 10 indicates a bail to which as shown the lock dog 8 is pivotally connected, the 60 ends of said bail being mounted on the projecting end of said shaft. Said shaft 7, as in the prior patent, should be provided with a finger piece at one end, by means of which it may be rotated. Extended transversely 65 through one of the joints of the pipe elbow 6 is a bolt 11, on the central portion of which a guide sheave 12 is loosely journaled.

A wire or small metallic cable 13 is attached at its lower end to the central portion of the 70 windlass shaft 7, and is passed over the guide sheave 12. The construction so far described, is that of my said prior patent. In the said prior patent however, the upper end of the cable was connected to an anchor bar, 75 which in turn, was applied inside of the main flue of the chimney. This necessitated tightening of the locking device to rigidly secure sections of the pipe together as the pipe was inserted into the pipe flue of the chimney. 80 In practice, I have found it to be a very much easier matter to tighten the lock device and to rigidly secure together the sections of the pipe before the pipe is raised or applied in operative position, and hence as the feature 85 of my present invention, I provide a so called supplemental lock device, which may be applied to the chimney before the pipe is applied thereto and which may be connected directly or indirectly to the main locking 90 device, after the latter has been tightened to lock together the sections of the pipe. This permits the main locking device to be employed to lock together the stove pipe sections before the said stove pipe is 95 raised or applied either to the stove or to the chimney. As preferably constructed, this supplemental locking device comprises an anchor bar 14 and a pair of wires or small cables 15 attached thereto. To 100 afford a convenient connection between the main and the supplemental locking devices, a bolt 16 is passed diametrically through the extended end of the horizontal portion 5 of the stove pipe and the upper end of the 105 wire or cable 13 is attached to the intermediate portion thereof. The ends of this bolt 16 are slit as shown at 17, so that they are

adapted to receive the outer ends of the short wires 15. Furthermore, the slit ends of said bolt 16 are threaded and provided with nuts 18, which when tightened, rigidly clamp the 5 wires 15 against the inner extremities of the slits 17, and thus rigidly lock the main and the supplemental locking devices together.

As is evident, when the delivery end of the 10 stove pipe is inserted into the flue 3, and the wires 15 are secured to the bolt 16 by the nuts 18, as shown in the drawings, said pipe will be firmly locked to the chimney and the said wires 15 and bolt 16 constitute an extension of the main lock device.

15 The wires 15 may be connected to the wire 13 in various different ways, all within the scope of my invention. For instance, said wire 15 might be twisted or bent around the ends of the bolt 16, but this would not be as 20 good construction as that illustrated in the drawings. The supplemental lock device arranged to operate as above described, constitutes an important improvement on the lock device disclosed and broadly claimed in 25 my prior patent above identified.

What I claim is:

1. The combination with a chimney flue and a sectional stove pipe discharging into the same, of an anchoring bolt extended 30 through the upper end or discharge section of said pipe, a main cable or wire located within and extended through said pipe and anchored at one end to said anchor bolt, and at its other end to the lower end or receiving 35 section of said pipe, an anchor bar engageable with the said chimney flue, and a pair of wires connected to said anchor bar and se-

cured to the ends of said anchor bolt outside of said pipe.

2. The combination with a sectional stove 40 pipe, of anchor bolts extended transversely through the end sections of said pipe, a main wire or cable extended through said pipe and anchored at its ends to said bolts, the said anchor bolt in the upper end section of said pipe having slit ends and provided with clamping nuts, and a supplemental lock device, comprising an anchor bar and a pair of wires connected thereto, the outer ends of which wires are passed through the slit ends 45 of said anchor bolt and are rigidly but detachably clamped thereto by the said clamping nuts.

3. The combination with a chimney flue and a sectional stove pipe having an elbow 55 and arranged to discharge into said flue, of a windlass and an anchor bolt mounted in said pipe, a sheave equipped bolt mounted in said elbow, a main wire or cable located in said pipe and elbow and connected to said anchor 60 bolt and to said windlass and passed over said sheave and arranged to be tightened by said windlass and a supplemental lock device comprising an anchor bar engageable with said chimney flue, a pair of wires and 65 means for detachably securing the outer ends of said wires to the ends of said anchor bolt outside of said pipe.

In testimony whereof I affix my signature in presence of two witnesses.

ALFRED W. HOYER.
